UNITED STATES PATENT OFFICE

FELIX F. McCUE, OF MILLERS FALLS, MASSACHUSETTS, ASSIGNOR TO MILLERS FALLS COMPANY, OF MILLERS FALLS, MASSACHUSETTS, A CORPORATION OF MASSACHUSETTS

PLANE

Application filed March 2, 1925. Serial No. 12,492.

This invention relates to a plane, and aims to provide a device of this character of improved construction.

It is an object of the invention to construct a plane in which the number of parts required is reduced.

A further object of the invention is that of furnishing a device of the type stated in which the mechanism may be adjusted with greater facility and with less likelihood of becoming disarranged.

Specifically stated, it is a further object of the invention to provide a plane in which the frog is associated with the bed of the tool in an improved manner, and which frog may readily be adjusted to vary the throat opening without the necessity of removing the plane knife assembly.

An additional object is that of providing a device of the character stated which will efficiently perform the purposes for which it is intended, and which will also be economically and readily manufactured and easily assembled.

Other objects of the invention will in part be obvious and will in part appear herein-after.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Fig. 1 is a sectional side elevation of one form of plane embodying the improved construction of the present invention;

Figs. 2 and 3 are fragmentary transverse sectional views of certain parts of the plane, and taken along the lines 2-2 and 3-3 and in the direction of the arrows indicated in Fig. 1; and

Fig. 4 is a fragmentary sectional side view of certain of the mechanism as illustrated in Fig. 1, but showing a slightly different construction of the parts.

Referring primarily to Figs. 1, 2 and 3, it will be noted that a plane has been illustrated which includes a body having a bed 5, a knob 6 being secured in position at the front of the bed, and a handle 7 being associated with the rear end thereof. This bed is, in the usual manner, formed with an opening or throat 8, into which the lower end of a knife assembly extends.

The latter, if desired, may include a blade 9 provided with a cap-plate 10, these units being secured against relative movement by means of a clamping-bow 11, which may be provided with a locking-member 12 at its upper end. The knife or blade, together with the cap-plate may be adjusted by a feeding screw and lever 9', and the blade may be rocked by a shifting lever 12'. In the present instance all of these units are carried by a frog having a main body-portion 13 comprising an inclined bit-bed or seat, a rear projection with an underface or seat, the bed portion terminating in a face 23 engaging with the plane bed, the frog being adapted to be secured to the bed 5.

In order to effect such attachment a rib 14 extends from the upper face of the plane bed, and between the side walls 15 of the latter. This rib is formed, in the present instance, with three transversely-extending screw-threaded bores, within which the shanks of correspondingly threaded members are disposed. The central member 16 terminates in a grooved and slotted head 17 extending beyond the rear face of the rib 14. The two outermost screw-threaded members 18 and 19 have their ends extending beyond the transverse faces of the rib, and adjacent their rear ends are preferably formed with a slot or groove, so that they may be turned by means of a screw driver or similar implement. A screw 20 is carried by the frog 13, and serves to secure a fork 21 in such position that its arms extend within the groove of the head 17, and, consequently, upon this head being turned to move the shank 16 relatively to the frog the latter will be moved longitudinally of the bed 5.

The bed of the plane is in this exemplification formed with a step or bench 22 adjacent

the rear edge of the throat 8, and this step may be extended at points beyond the side edges of the frog in order to provide what might be termed guiding-lips 23,—it being noted that the frog body is extended as at 24 so that it may bear adjacent its forward edge portion against the face of the step 22. Similarly, if desired, the upper edge of the rib 14 may be provided with guiding-lips 25 adjacent the side edges of a second extension 26 forming a part of the frog body, and thus the movements of the frog will be properly confined with respect to the plane body. While this movement, as in Figs. 1, 2 and 3, is in a plane parallel to the upper face of the tool body, it is obvious that, if desired,—as in Fig. 4—the forward edge of the frog might be extended as at 29 so as to be capable of projecting into the throat 8; and the rear edge of the latter might be beveled as at 30,—the under face of the frog which cooperates therewith being correspondingly beveled. In this instance the upper face of the rib 31 corresponding to the rib 14 is also beveled as at 32, and that face of the frog which cooperates with this portion is also correspondingly surfaced.

The extended portion 24 of the frog is continued in the form of a rearwardly-projecting portion, which has its upper surface inclined as at 27 to cooperate with the correspondingly beveled end-portions 28 of the screws 18, 19.

With reference to the construction shown in Figs. 1 to 3, it will be understood that the plane parts are assembled in the usual manner, and that the size of the throat opening may be readily diminished without disturbing the setting of the blade by simply projecting the screw 16 within its bore, thus advancing the frog body, together with the parts associated therewith. Thereafter, by projecting the screws 18, 19 the inner ends of the latter will be forced into intimate contact with the upper face 27 of the frog extension. During the movement of the frog it will be obvious that it will be confined to a proper path by virtue of the guiding expedient herein suggested, and by the use of the screws 18, 19 it will be apparent that a retraction and raising of the frog will be prevented, due to the fact that the inclined cooperating faces 27, 28 will coact to prevent such movements.

In the form of tool illustrated in Fig. 4 it will be obvious that in order to constrict the size of the throat opening the same procedure will be resorted to as in connection with the tool aforescribed, but by means of this latter construction it will also be apparent that the rear face of the blade will be supported at a point immediately adjacent its cutting edge incident to the frog extension 29. It will be understood in connection with the types of devices shown in Fig. 4 that simultaneously with the adjustment of the throat

opening the blade will be extended or retracted, this being true incident to the surfaces 30—32. If, however, it is desired to vary the throat opening without effecting a consequent projection or retraction of the cutting edge, this may readily be accomplished by simply resetting the blade after the frog has once been adjusted.

In both forms of the device it will be apparent that the adjustment of the throat opening may readily be made without disturbing the knife assembly or the relationship of the same to the frog, and during such adjustment all units will be properly guided so that it will not be necessary to resort to many complicated adjustments, and at least a partial disassembly of the tool, in order to reset the parts. Obviously, the size of the throat might be increased by simply reversing the order of operation which has been previously described, and when the parts have once been locked it will be obvious that a shifting of the same is virtually precluded.

From the foregoing it will be appreciated that the objects of the invention have been accomplished, and since certain changes may be made in the above construction, and different embodiments of the invention could be made, without departing from the scope thereof, it is intended that all matter contained in the above description, or shown in the accompanying drawings, shall be interpreted as illustrative and not in a limiting sense.

It is also to be understood that the following claims are intended to cover all of the generic and specific features of the invention herein described, and all statements of the scope of the invention which as a matter of language might be said to fall therebetween.

Having described my invention, what I claim as new and desire to secure by Letters Patent is:

1. A plane, including, in combination, a bed formed with a throat having a portion of its rear edge beveled, a frog having a surface adapted to cooperate with said beveled edge and an extended portion projectable into said throat, a rib adjacent said throat and having its upper edge beveled in a plane substantially corresponding to the beveling of the throat edge, the frog adjacent a point at which it contacts with said rib being correspondingly surfaced, said frog presenting a rearwardly-extending surface inclined at an angle to said first-named surfaces, and a screw carried by said rib having an end tapered to correspond to said latter surface and contacting therewith for preventing movements of said frog relatively to said bed.

2. A plane, including, in combination, a bed formed with a throat, a rib associated with said bed and disposed rearwardly of said throat, a frog, means cooperating with

5 said bed and frog for shifting the latter longitudinally of the former, said frog being formed with a surface extending at an angle to the direction of such shifting, and a screw extending through said rib and having its axis disposed substantially parallel to the direction of such shifting, the inner end of said screw contacting with said frog surface to lock the parts against relative movements.

10 3. A plane including in combination, a bed formed with a blade-receiving throat and with an upwardly extending rib to the rear of said throat, a blade-supporting frog comprising a bit-bed or seat and having a forward portion provided with a lower face adapted to rest on said bed and a rear projecting portion adapted to rest on said rib and formed with a recess between said portions adjacent said rib, said frog being also 15 formed with a projecting member extending rearwardly from the bed portion of said frog and having an upper working face extending beneath said recess, means for adjusting said frog with respect to said bed, 20 and screw means including a pair of members extending through said rib for engaging a part of said working face, at least one of said members having a downwardly and rearwardly engaging portion producing a 25 wedging action whereby said frog is rigidly held upon said bed.

30 4. A plane including in combination, a bed formed with a blade-receiving throat and with an upwardly extending rib to the rear 35 of said throat, a blade-supporting frog comprising a bit-bed or seat and having a forward portion provided with a lower face adapted to rest on said bed and a rear projecting portion adapted to rest on said rib 40 and formed with a recess between said portions adjacent said rib, said frog being also formed with a projecting member extending rearwardly from the bed portion of said frog and having an inclined upper working face extending beneath said recess, means for adjusting said frog with respect to said bed, and means including a member extending through said rib for engaging a part of 45 said working face, said projecting member thereby rigidly holding said frog against 50 said bed.

In testimony whereof I affix my signature.
FELIX F. McCUE.
